8 Claims

Int. Cl. H01r 5/08; B21d 31/00, 37/12

This invention relates to an apparatus for trimming the ends of wires and crimping an electrical connecting device onto the trimmed ends.

The co-pending application of Richard Ellwood Reem et al., Ser. No. 539,230, filed Jan. 7, 1966, now U.S. Patent No. 3,328,872, discloses and claims connector crimping devices of a type adapted to crimp a connector onto the ends of wires extending axially towards each other to form a splice connection between the wires. A distinguishing feature of this Reem et al. tool is that the ends of the wires are trimmed prior to crimping so that the slack can be drawn out of the wires when the splice connection is made. A further distinguishing feature and advantage of this Reem et al. tool is that the manipulative operation of positioning the wires in the tool is greatly simplified as compared with prior art methods and devices so that a high production rate can be achieved by a technician using the tool.

The present invention relates to an apparatus for accomplishing many of the same objectives as the Reem et al. tool and performing similar, and additional, operations. The present invention is particularly directed to an apparatus which permits the use of relatively short connecting devices to make such splices and to an apparatus having improved means for locating the wires in the connector and holding them in position while the connector is being crimped onto the wires.

It is accordingly an object of the invention to provide an improved tool for crimping an electrical connector onto the ends of wires. A further object is to provide a tool for trimming the ends of wires and making a splice connection between the wires. A further object is to provide a tool having improved means for locating the wires and holding them in position while the splice connection is being made. A further object is to provide a tool adapted to crimp relatively short splice connectors onto the ends of wires. A still further object is to provide a relatively fool-proof and easily operated device which can be used by relatively inexperienced personnel with very little prior training.

These and other objects of the invention are achieved in a preferred embodiment of the tool adapted to trim the ends of wires extending axially towards each other and crimp an open U-type connecting device onto the overlapped ends of the trimmed wires. One preferred form of the invention comprises a pair of crimping members, such as a conventional crimping die and crimping anvil, which are normally disposed in parallel spaced-apart relationship and which are movable relatively towards and away from each other along a predetermined path. One of these members, the crimping die, is adapted to bend the sidewalls of an open U-type connector inwardly towards each other and crimp the connector onto the ends of the wires. The other member, the anvil, is adapted to support the connector during the crimping operation. The ends of the crimping members define wire shearing planes in which a pair of wire shearing members are mounted. These shearing members are normally disposed beside the path of relative movement of the crimping members and between the crimping members when they are in their open positions. The shearing members are movable, independently of the crimping members, towards and past one of the crimping members and

2

cooperate with the one crimping member to perform a wire shearing operation. A wire locating means is provided in the form of a pair of plate-like members mounted against the shearing members, each plate-like member having first and second wire holders for holding the wires during the crimping operation. The first wire holders in these plate-like members are located on the sides of the shearing members which are adjacent to the crimping anvil and the second wire holders are located on the side adjacent to the crimping die which cooperates with the shearing members to cut the wires. In use, each wire is positioned with its axis extending through a first and then a second wire holder in the two plate-like members so that the wires will be positioned with their axes extending between a first shearing member and the crimping anvil thence between the crimping die and the crimping anvil thence between a second shearing member and the crimping die and through a second wire holder with the end portion of the wire extending externally of this second wire holder. Upon movement of the shearing members towards the die, these end portions of the wires will be severed in the severing planes and upon subsequent movement of the die relatively towards the anvil, an electrical connector supported on the die will be crimped onto the trimmed ends of the wires. The wires in the crimped connection will be in overlapping parallel relationship so that a minimum length in the finished connection is achieved.

In the drawings:

FIGURE 1 is a perspective view of an uncrimped connector intended for use in the disclosed embodiment of the invention;

FIGURE 2 is a perspective view of a crimped connection;

FIGURE 3 is a side view with parts broken away of one form of hand tool in accordance with the invention;

FIGURE 4 is a front view of the upper portion of the tool of FIGURE 3;

FIGURE 5 is a fragmentary perspective view showing the anvil, the crimping die, and the wire positioning and cutting means of the tool of FIGURE 3;

FIGURE 6 is a fragmentary perspective view showing the anvil, the anvil block, and the cutters;

FIGURES 7, 8, and 9 are fragmentary front views showing the wire positioning means, the wire cutters, and portions of the crimping die and anvil and illustrating the operation of the tool;

FIGURE 10 is a plan view of the two wire positioning plates, these plates being disposed in back-to-back relationship for the purpose of illustrating the depth of the wire locating slots.

FIGURE 11 is a fragmentary perspective view of an alternative embodiment of the invention;

FIGURE 12 is a view similar to FIGURE 11 but showing the manner in which the wires can be positioned to produce a butt splice;

FIGURE 13 is a perspective view of a butt splice;

FIGURE 14 is a view similar to FIGURE 11 but showing the manner in which the wires can be positioned to produce a tap connection; and

FIGURE 15 is a perspective view of a tap connection.

Referring first to FIGURES 1 and 2, one type of connector 2, which is adapted to be crimped by a tool in accordance with the invention, has a web portion 4 from which sidewalls 6 extend. A pair of spaced-apart tongues 8 are struck up from the web adjacent to the ends of the connector and have side-by-side notches 10, the notches of each tongue being axially aligned with the notches of the other tongue. Advantageously, plastic insulating film 12 of a material such as Mylar (polyethylene terephthalate) is bonded to the external surface of the connector and extends beyond the edges of the sidewalls and the ends of

the connector so that the completed crimped connection, FIGURE 2, will be entirely encased in the insulating film. In the finished crimped connection, the wires 14, 16 overlap with each wire being disposed in a set of the notches 10 in the tongues. As explained in the above-identified Reem et al. application the notches are preferably of a width such that they will penetrate the insulation of the wire and establish electrical contact with the conducting core thereof thus avoiding the necessity of stripping this insulation in a separate operation.

One form of apparatus in accordance with the invention (FIGURES 3-6), comprises a tool 18 having a frame 20 with a flanged head 22 at one end thereof against which the crimping dies are mounted as will be described below. A fixed handle 24 is secured to the opposite or lower end of the frame and has a generally channel-shaped cross section with sides 26 and a web 28. The sides 26 extend along opposite sides of the frame and are secured thereto by suitable fasteners 30. A movable handle 32 has an end portion 34 which is received between a pair of spaced apart ears 36 on an anvil block 38 (FIGURE 6) which is pivoted to the anvil block by means of a suitable pin 40 which extends through the end of the handle and through the ears. The ends of this pin extend beyond the ears and have rollers 42 mounted thereon to permit movement of the handle and the anvil upwardly and towards the head portion 22 of the tool. A separate cover plate 46 is mounted over the side of the frame into which the handle extends and is secured to the frame by suitable fasteners.

A link means 50 is pivoted at 52 to the opposite sides of the movable handle 32 and is also pivoted at 54 to the lower end of the frame, a suitable channel or slot 56 being provided in the frame 20 for reception of the ends of the link means. A full stroke compelling mechanism comprising a ratchet bar 58 and a pawl mechanism contained in a housing 60 is provided between the handles 26, 32 to ensure that the operator will fully close the handles when he makes a crimped connection. Devices of this type are commonly provided on crimping tools and are described in detail in U.S. Patent No. 2,618,993.

The anvil block 38 has a transversely extending anvil 68 on its upper side which is adapted to support the connector 2 during the crimping operation. It will be apparent that upon closure of the handles, that is, upon relative movement of the handle 32 towards the fixed handle 26, this anvil block and the anvil 68 will be moved relatively upwardly towards the crimping die which is described below.

The crimping die 76 is composite structure comprising three substantially similar sections 78, 80, 82 secured together by means of suitable rivets 84. A fastener 86 extends through the head portion 22 of the frame and into the center die section 80 to hold the die in position. Each section of the die has a cavity 88 having generally sharply convergent sidewall portions 89 which merge with sidewall portions 90. These sidewall portions, in turn, are reversely curved to form a cusp 92. The external edges of the die sections are bevelled as shown at 94 to assist in smoothly curling the sidewalls of the connector without cutting or otherwise damaging the insulating film on the connector. The anvil is somewhat longer than the die and extends beyond the die at each end.

It will be apparent that the die and anvil constitute a pair of crimping members which are effective upon relative movement towards each other to bend the sidewalls of the connector into crimped engagement with the conductors. The structure for locating the wires in the connector and trimming the ends of the wires immediately prior to the crimping operation will now be described.

The cutting or shearing members 98 are mounted in shearing planes defined by the ends of the die. Each cutter 98 has a lower portion 102 which is provided with an elongated notch 104. The lower portions 102 of the cutters are disposed adjacent to sides of the anvil block and

a pin 106 extends through this block and has its ends disposed in the notches 104 to provide a lost motion connection between the cutters and the anvil block. Thus, when the anvil block moves upwardly, as viewed in the drawing, this pin will move against the upper sides 110 of the notches after limited movement and move the cutters upwardly. Upon relative downward movement of the anvil block, this pin will move against the sides 108 of the notches and pull the cutters downwardly. Adjacent to their upper ends, the cutters 98 have forwardly extending arms 112, the upper sides 114 of which function as shearing members in cooperation with the sides of the crimping die as will be described below. The lower sides of these arms 112 have semi-circular surfaces 116 and a cusp 118 which conforms to the radius of the dies themselves. As will also be explained below, these lower sides cooperate with and, in effect, become part of, the crimping die during the final stages of the operating cycle. The outer ends of the cutters are of reduced thickness as shown at 120 and are received within slots formed by a guide plate 122. This guide plate is secured to the frame and extends over the front portion of the die and has inwardly directed flanges 124. These flanges are spaced from the sides of the die to provide channels or guideways for the ends 120 of the cutters.

When the cutters move upwardly, as viewed in the drawing, past the sides of the crimping die, their upper surfaces 114 will shear any wires extending between these upper sides of the arms and the crimping die. There will now be described a locating means which insures that the wires will always be properly located in the tool to bring about severing of the ends of the wires and positioning of the wires in side-by-side parallel relationship.

The wire locating means of the embodiment of FIGURE 3 comprises a pair of wire guide members 126, 128 in the form of plates secured to and against the external sides of the cutters 98. While these plates may be of any suitable material, it has been found advantageous to make them of a relatively tough and durable plastic such as a relatively firm, non-porous polyurethane for reasons which will be apparent from the description below. Each wire guide plate 126, 128 is provided with a first slot 130, 130' and a second slot 132, 132'. The slots 130, 130' are disposed below the arms 112 of the wire cutters or shearing members. The slots 132, 132' are disposed above the arms 112 and between these arms and the crimping die. The slots 130 and 132' are relatively shallow, that is, they extend inwardly from the front edge of the guide plates 126, 128 only a relatively short distance. The slots 130', 132 on the other hand, are relatively deeper than the slots 130, 132'. It will also be noted that the slots 132, 132' are cylindrical at their inner ends as shown at 134 and these slots extend generally obliquely and downwardly towards the center line of the tool. The slots 130, 130', on the other hand, are straight and extend normally of the center line of the tool.

The width of the slots is advantageously somewhat less than the diameter of the wires 14, 16 so that the wires, after being forced in the slots, will be resiliently gripped and held in position. A relatively firm polyurethane material, as described above, is advantageous in that this gripping effect will be achieved.

In use, and when the anvil is in its down or separated position with respect to the die, the wires are located in a manner such that the wire 16 extending from the right, as viewed in the drawing, is positioned first in the slot 130' of plate 128 and then in the slot 132 of plate 126, these slots constituting the relatively deeper slots described above. The wire 14 extending from the left is positioned in the slot 130 of guide member 126 and in the slot 132' of the guide member 128. When the wires are thus positioned, the wire 16 in the slots 130', 132 will be behind the other wire and the two wires will extend in parallel spaced-apart planes. The end por-

tions of the wires will extend between the upper surface or cutting sides 114 of the arms 112 while the entering portions of the wires will extend beneath these cutter arms and will not be severed.

After thus positioning the wires, the operator merely positions a terminal on the anvil and squeezes the handles until the crimping anvil moves through the limit of its travel towards the die. During initial movement of the crimping anvil, the terminal will be raised and the pin 106 will move against the sides 110, the shearing members will be moved upwardly until the sides 114 move past the sides of the crimping die thereby to cut the projecting end portions of the wires (FIGURE 8).

After this trimming operation, the cut ends of the wires will be positioned in side-by-side relationship in the connector and the sidewalls of the connector will be bent inwardly into crimped engagement with the wires (FIGURE 9).

An overall advantage of the invention is that it permits a crimped connection having a minimum length since the wires are overlapped in the finished crimped connection. This achievement of a relatively short splice connection has substantial benefits, particularly, in the communications field where telephone cables containing up to 2700 pairs of wires must be spliced. It can readily be seen that any saving in bulk in the crimped connection will be reflected in a small overall increase in the diameter of the cable at the location of the splicing operation and is highly desirable for that reason.

In addition to the advantage of a relatively small and compact splice, the invention achieves accurate location of the wires in the crimped connection with their axes extending side-by-side and parallel to each other as shown in FIGURE 2. The wires are under complete control during all stages of the operation by virtue of the wire holders and the different depths of the slots in these wire holders. The wires will thus never be crossed in the finished splice and consistent electrical results will be achieved. Finally, it should be noted that the scrap ends of the wires which are severed in the shearing planes at the ends of the crimping members are outside of the connector after the shearing or cutting operations have been carried out. These scrap ends thus do not interfere with the crimping operation and need not be removed by the technician in a separate operation.

FIGURE 11 shows an alternate embodiment of the invention having a wire guiding and holding arrangement which is somewhat different from the corresponding elements of the embodiments of FIGURE 3. In the embodiment of FIGURE 11, the anvil block 38, the anvil 68, and the crimping die 76 are substantially the same as the corresponding parts shown in FIGURE 5. The spaced-apart cutting bars 136 in this embodiment have notches 140 at their lower ends 138, the width of these notches being substantially equal to the diameter of the pin 106 so that, unlike the embodiment of FIGURE 3, there is no lost motion connection between the cutter 136 and the anvil block 38. In other words, if the anvil block moves upwardly, the cutter bars will also move upwardly by the same amount as the anvil block.

The shearing arms 142, which extend from the bars 136 have lower and upper sides 144, 146 and the edges of these arms perform the wire cutting operations as previously described. The wire guides 148, 150 are secured by suitable fasteners to the outwardly facing sides of cutter bars 136 and are advantageously made of a suitable plastic material such as polyurethane as previously described. Referring particularly to the wire guide 148, this member is provided with an inwardly directed slot 152 and a forwardly directed arm 153 immediately below the slot 152. The guiding of wires is facilitated by means of a bent wire guide member 154 having an upper arm 156 which extends into the slot 152 and a lower arm 158 which extends beneath the arm 153 of the guide member 148. The end portion 160 of the arm 158 is bent upwardly and

extends into a suitable opening on the underside of the arm 153. The wire guide 150 is provided with an identically bent wire guide 162 having an upper arm 164 and a lower arm 166, the upper arm extending into a slot 168 in the guide 150 and the lower arm extending beneath the arm 170 of the guide 150.

In use, the wire 16 which extends from the right in FIGURE 11 is positioned between the end portion 160 and the surface of the guide 150 and is led above the left hand cutter bar 136 and through the slot 152 of the guide 148. The wire 14 which extends from the left in FIGURE 11 is similarly located between the end 160 and the guide 154 and the surface of the wire guide 148 and is led above the upper surface 146 of the arm 142 of the right hand cutter bar and through the slot 168. After the wires have been so positioned, the tool handles are closed and the wires 14, 16 are trimmed in the planes of the ends of the die. The connector 2 is crimped onto the trimmed wire ends in the manner previously described.

A comparative advantage of the embodiment of FIGURE 11 is that the lost motion connection between the cutter bars 136 and the pin 106 is not required because of the fact that the portions of the wires held between the ends 160, 167 of the bent wire guides and the surfaces of the guides 148, 150 are permitted to remain stationary while the cutter bars move upwardly after the severing operation has been carried out. The upward movement of the cutter bars and the guides 148, 150 without upward movement of the wires is permitted because of the fact that the slots defined by the ends of the bent wire guides 160, 167 and the surface of the guide plates 148, 150 extend upwardly as viewed in the drawing and the wires can be moved relatively out of the slots during the final portion of the stroke of the tool.

FIGURE 12 illustrates the manner in which a pigtail splice as shown in FIGURE 13 can be formed with the embodiment of FIGURE 11. In accordance with this aspect of the invention, the two wires which are to be spliced are positioned with their axes extending between the end portion 160 of guide member 154 and the surface of the member 148, thence over the upper surface 146 of arm 142 and above the upper arm 164 of the guide 162. When the wires are located in the tool in this manner, the end portions of the wires will be severed in the plane of the right hand side of the crimping die 78 by the arm 142 and the severed ends will be crimped onto the connector as shown in FIGURE 13.

FIGURE 14 illustrates the manner in which a T-tap connection can be made with a tool of the type shown in FIGURE 11. The T-tap, FIGURE 15, comprises a through wire and a tap wire as shown. In making a connection of this type, through wire 170 is located beneath the guide members 154, 162 and the tap wire is positioned beneath one of these guide members and lead above the other guide member, the guide member 162 are this instance. In accordance with this embodiment, when the die and anvil are moved relatively toward each other and the cutters are moved relatively past the die, the tap wire will be severed and the through wire will not be severed since it is not located between the cutting arms. The connector will then be crimped onto the trimmed tap wire and the through wire as shown in FIGURE 15.

Changes in construction will occur to those skilled in the art and various apparently different modifications and embodiments may be made without departing from the scope of the invention. The matter set forth in the foregoing description and accompanying drawings is offered by way of illustration only. The actual scope of the invention is intended to be defined in the following claims when viewed in their proper perspective against the prior art.

What is claimed is:

1. Apparatus for trimming the ends of a pair of wires extending axially towards each other and crimping an

open-U type connecting device onto the trimmed ends, said apparatus comprising, a pair of crimping members normally disposed in parallel spaced-apart relationship, said members being movable relatively towards and away from each other along a predetermined path, said members being adapted to support and crimp an open-U type electrical connector, the end portions of said crimping members defining wire shearing planes, a pair of wire shearing members, one of said shearing members being disposed in each of said planes, said shearing members being normally disposed beside said path at locations between said crimping members, said shearing members being movable parallel to said path and in said planes towards and past a first one of said crimping members to shear said wires, and wire locating means on each of said shearing members, each wire locating means having first and second wire holders, said wire holders of each locating means being arranged on opposite sides of said shearing members with said first wire holders located on the sides of said shearing members adjacent to said second crimping member and said second wire holders being located on the sides of said shearing members adjacent to said first crimping member whereby, each wire can be positioned in a first and second wire holder to locate said wires with their axes extending through a first holder thence between a first shearing member and the second one of said crimping members thence between said crimping members thence between a second shearing member and said first one of said crimping members thence through a second holder, the first holder of the one locating means and the second holder of the other locating means lying in one plane, and the remaining wire holders lying in another plane extending parallel to, and beside, said one plane whereby, said wires will be positioned in side-by-side relationship when held in said wire holders, and during movement of said shearing members towards and past said first one of said crimping members, the end portions of said wires are severed in said shearing planes, and during subsequent movement of said crimping members relatively towards each other, an open-U type connecting device is crimped onto the overlapping cut ends of said wires, with said wires being in side-by-side parallel relationship in said connecting device.

2. A device as set forth in claim 1 wherein said first one of said crimping members comprises a crimping die and said second crimping member comprises a crimping anvil, said crimping anvil being adapted to support said connector, and said die having forming surface portions opposed to said die, said forming surfaces being adapted to bend the sidewalls of said connector into crimped embracing relationship with said wires.

3. A device as set forth in claim 2 wherein said wire holders comprise slots in said wire locating means.

4. A device as set forth in claim 2 wherein said shearing members have said side portions opposed to said anvil which conform to said forming surfaces of said die, said shearing members being movable into alignment with said die during shearing of said wires whereby said side portions cooperate with said die to crimp said connector onto said wire.

5. In a device of the type intended for trimming the ends of wires and crimping an open U-type connecting device onto the trimmed ends, said device comprising a crimping die and a crimping anvil, means for moving

said die and anvil relatively towards and away from each other along a predetermined path, a pair of shearing members disposed between said die and anvil and in the planes of the ends of said die, said shearing members being movable relatively towards and past said die whereby said shearing members cooperate with the ends of said die to shear wires extending through the planes of the ends of said die, the improvement to said apparatus comprising:

10 wire locating and holding means on each of said shearing members, said locating and holding means comprising means for locating a pair of wires extending axially towards each other in side-by-side relationship between said die and anvil with each wire extending between said anvil and one shearing member 15 thence between said die and anvil thence between the other shearing member and said die whereby, upon actuating of said apparatus, the end portions of 20 said wires are trimmed in the planes of the ends of said die and a connector supported on said anvil is thereafter crimped onto the overlapping wire ends.

6. A device as set forth in claim 5 wherein said locating and holding means comprises plate means on said shearing means, said plate means having slots for reception of said wires.

7. A device as set forth in claim 6 wherein one slot in each locating and holding means extends laterally of said path and the other of said slots extends parallel to said path and has an open end facing said anvil.

30 8. In an apparatus of the type intended for trimming
the ends of wires and crimping a connecting device hav-
ing an open side onto the trimmed ends, said device com-
prising a crimping die and a crimping anvil, means for
moving said die and anvil relatively towards and away
35 from each other along a predetermined path, a pair of
shearing members disposed between said die and anvil
and in the planes of the ends of said die, said shearing
members being movable relatively towards and past
said die whereby said shearing members cooperate with
40 the ends of said die to shear wires extending through the
planes of the ends of said die, the improvement to said
apparatus comprising:

45 a pair of wire locating devices disposed on each side of
said apparatus, each wire locating device being
adapted to guide an incoming wire past the non-
shearing side of one shearing means, past the shear-
ing side of the second shearing means, thence be-
yond of said apparatus whereby,
upon actuating of said apparatus, the end portions of
50 said wires are trimmed in the planes of the ends of said
die and a connector supported on said anvil is thereafter
crimped onto the overlapping wire ends.
